UNITED STATES PATENT OFFICE.

JOSEPH L. MEDICI AND CHARLES O. MEDICI, OF DETROIT, MICHIGAN.

CONDIMENT HOLDER.

1,425,328.

Specification of Letters Patent. Patented Aug. 8, 1922.

Application filed February 14, 1921. Serial No. 444,798.

To all whom it may concern:

Be it known that we, JOSEPH L. MEDICI and CHARLES O. MEDICI, citizens of the United States of America, residing at Detroit, in the county of Wayne and State of Michigan, have invented certain new and useful Improvements in Condiment Holders, of which the following is a specification, reference being had therein to the accompanying drawings.

The invention relates to condiment holders of that type in which a plurality of different materials, such for instance as salt and pepper, may be held in separate compartments of the holder and alternatively discharged therefrom. It is the object of the invention to obtain a simple construction, which is easily manipulated and which may be made in ornamental form, and to this end the invention comprises the construction as hereinafter set forth.

In the drawings:

Figure 1 is a perspective view of the holder, with the perforated cover and securing means therefor detached;

Figure 2 is a vertical central section through the holder;

Figure 3 is a section in a plane at right angles to Figure 2;

Figure 4 is a plan view partly broken away.

A is an outer casing, which may be of any desired contour, but which as shown is of polygonal form. The space within this casing is divided by a partition B into two compartments for holding respectively the salt and the pepper, or other condiments used. C is a cover for the casing, provided with perforations D and D' on opposite sides thereof, arranged above the respective compartments. This cover is detachably secured by suitable means, such as the screw-threaded ring E and cooperating members, such as a lug F on the casing A and notch G in the cover C, to hold the latter in proper registration.

To control the alternative discharge of material from the compartments, and also to prevent clogging, combined valve and scrapers are arranged adjacent to the inner perforated faces of the cover. These scrapers H and H' are of segmental spherical form, corresponding to the spherical inner face of the cover, and each scraper is provided with an actuating device operable from outside of the casing. Preferably, the actuating

mechanism is housed within the casing by forming upon the partition B a central hollow enlargement I. Within this member are resilient arms J, preferably a U-shaped resilient strip forming a pair of parallel arms respectively attached at their upper ends to the scrapers H and H'. There is sufficient space within the central chamber for the swinging of the arms J and J' so as to withdraw the scrapers H and H' from registration with the perforated portions D and D' of the cover, and when thus withdrawn, the device may be used as an ordinary salt or pepper shaker. The arms J and J' are operated by buttons K and K' extending out through the opposite sides of the casing A. These buttons are provided with shanks L and L', which pass through hollow lugs M and M' into the central chamber, where they are provided with heads N and N', bearing against the U-shaped member J. The arrangement is such that by pressing on one of the buttons, such as K, the arm J will be flexed, withdrawing the scraper H and permitting the material in the corresponding compartment to be shaken out through the perforations D. When pressure is released upon the button, the resiliency of the U-shaped arm will return the scraper to its original position, thereby performing the double function of closing the perforations and scraping or dislodging any accumulation of material which would clog said perforations. In the same manner the operation of the opposite button will actuate the other scraper.

In use, when the two compartments of the holder are filled, either condiment may be shaken therefrom by pressing one or the other of the buttons K and K', and by suitably labeling these buttons, the user will be aware of which one to press. There is no exposed mechanism to detract from the appearance of the holder, while the operating mechanism within is protected from contact with the condiment. The refilling of the holder may be effected either by removal of the cover, or if desired by stoppered filling apertures in the bottom.

It is obvious that by pressing both buttons simultaneously both condiments may be shaken from the holder.

What we claim as our invention is:

1. A condiment holder, comprising a casing having a partition for dividing the same into a plurality of compartments, a cover

- having perforated portions arranged above the respective compartments on opposite sides of said partition, closures for the perforations arranged inside of said cover, a 5 **U**-shaped resilient member for separately moving said closures arranged in a central compartment of said casing, and means operable from outside said casing for actuating said mechanism.
- 10 2. A condiment holder, comprising a casing having a partition for dividing the same into two outer compartments and a central compartment, a cover for said casing having perforations arranged above the outer 15 compartments, combined valve and scrapers arranged adjacent to the inner face of said cover and adapted to respectively close the perforated portions thereof, integral resilient shanks for said scrapers arranged in 20 said central compartment, and push-buttons operable from outside of said casing extending into said central compartment and operatively engaging said resilient shanks.
3. A condiment holder, comprising a casing 25 divided by a partition into a plurality of outer compartments and a central compartment, hollow lugs extending from the outer wall of said casing to said central compartment, a **U**-shaped resilient member arranged within said central compartment, valve and scraper members attached to the outer ends of said **U**-shaped member, a perforated cover adjacent to said valve and scraper members, and push-buttons having 30 operating shanks extending through said hollow lugs into engagement with the oppo- site sides of said **U**-shaped resilient member and forming operating means for moving said scrapers.
4. A condiment holder, comprising a casing 40 having a partition dividing the same into a plurality of outer compartments and a central compartment, a cover for said casing having perforations therein above the respective outer compartments, securing 45 means for said cover, combined valve and scraper members lying adjacent to the inner face of said cover and forming closures for the respective perforated portions, a **U**-shaped resilient shank member attached to 50 said valve and scraper members and extending downward in said central compartment, and push-buttons on diametrically opposite sides of said casing having shanks extending into said central compartment 55 into operative relation to said resilient shank member.
5. A condiment holder, comprising a casing having a partition for dividing the same into a plurality of compartments, a cover 60 having perforated portions arranged above the respective compartments, valves adjacent to said cover for the respective compartments, and a member provided with substantially parallel resilient integral arms secured to said valves for separately operating each in both directions of movement.

In testimony whereof we affix our signatures.

JOSEPH L. MEDICI.
CHARLES O. MEDICI.
